YARN CONTROL MEANS

Frederick J. Kent, Glen Rock, N. J., assignor to
Sipp-Eastwood Corporation, Paterson, N. J., a
corporation of New York

Application June 6, 1939, Serial No. 277,588

8 Claims. (Cl. 242—153)

This invention relates to yarn tension devices and particularly to such devices wherein the means for opposing the tensioning resistance comprises two elements, as grids, between which the yarn travels and one of which is normally urged crosswise of the yarn.

When yarn is traveling under control of a tension device of the specified type, and especially where the yarn is elastic and is traveling at high speed, inordinate vibration of the movable one of the two elements is set up and this results in the tension constantly varying and in the case of weak yarn is likely to disrupt it. In order to eliminate such vibration it has been proposed to damp such element, that is, to set up resistance thereto which, while yielding in character, will retard its movement either as caused on the one hand by the yarn or on the other by gravity or other expedient tending to urge said element against the yarn; for instance, it has been proposed to connect to said element means whose movement is resisted in some way by fluid, as a piston movable in a cylinder.

The object of this invention is to provide an improved tension device and especially of the class in which the movable element is subject to damping control, that is to say, so that greater uniformity of tension independently of the speed of the yarn and even in the case of very weak yarns will prevail than is possible with the use of any previous device of this type and so that the fabrication and assembling of the parts will be simplified and cheapened and a generally more efficient device result.

My invention further contemplates means, associated in a novel way with a tension device characterized more or less particularly as hereinafter set forth, but regardless of the presence or absence of any damping means controlling its movable tension element, for in some way signaling the operator when said movable element moves beyond that position past which it is normally held from moving by the thread when intact and taut.

In the drawings,

Fig. 1 is a perspective view of the device as seen from the front;

Fig. 2 is a side elevation thereof;

Fig. 3 is a front elevation;

Fig. 4 a section in the plane 4—4, Fig. 3;

Figs. 5 and 6 are plans of plates 20 and 22; and

Fig. 7 shows lever 19 in plan with its arm 19b removed.

A body or frame proper here is formed by a forked portion 1 having the arms of its fork

side by side and projecting forwardly; a forwardly and downwardly inclined wall or web 2 joining but extending short of the free ends of said arms; an arm 3 extending rearwardly from the portion 1 and, by having its free end upturned and formed with an eye 4, forming a thread guide; and a post 5 upstanding from the juncture of portion 1 and arm 3. Portion 1 at its rear side is provided with a socket 6 to receive an upstanding tongue on a bracket A of a creel frame where, as usual, the device will be associated with a creel—see Klein Patent No. 1,885,114, for instance; and arm 3 has a depending tongue 3a which may enter and fit a socket in the bracket to aid in maintaining the device 15 fixedly in position.

Forming with the frame-proper a part of the fixed structure of the device, though removable from such frame-proper, is a bifurcated element 7, here in the form of a wire, both legs thereof being approximately in the same horizontal plane. For supporting it the arms of the portion 1 have holes 8; this element, with its bend at one side of the frame-proper, has its legs received by the holes, and at the far side of the frame-proper the end of one leg may be upset to prevent unintentional removal of said element.

A somewhat elastic sheet-metal plate 9 surrounds the post 5, being held rigidly thereto by a screw 10, and it projects forwardly and has 30 along its forward straight edge an underneath groove 9a. Such plate forms another part of the fixed structure.

That tension member or grid which is fixed and also forms a part of the fixed structure may 35 be thus described: A metal plate 11 along a line parallel with and near one long edge thereof has portions 11a pressed in one direction and intermediate portions 11b pressed in the opposite direction out of the original plane of the plate, thus providing the plate with what amounts to a tubular portion, here in skeleton form, and the bore of such tubular portion receives the forward leg of element 7. Projecting in a direction transversely of the axis of such bore the plate 40 has spaced parallel fingers 11c and in the assembled state of the parts the free ends of these fingers are engaged in the groove 9a of plate 9, whereby element 7 and such plate 9 hold the member 11 in fixed position. The fingers are 45 all curved more or less to the contour of a cylinder common to them and so that their concave sides are forward.

That tension member or grid 12 which is movable is in all respects substantially a counterpart 55

of the member 11, to wit, having a tubular portion 12a formed substantially the same as the tubular portion 11a-11b of member 11 and a row of spaced curved projections 12b like the 5 fingers 11c, but the concave sides of said projections in this case are presented rearwardly. The bore of tubular portion 12a receives the rear leg of member 7, which therefore forms a bearing on which member 12 is pivoted. Member 12 is 10 confined against axial displacement by the arms of the forked portion 1 of the frame, and said projections are arranged so that when the member tilts forwardly they will pass freely between the fingers of member 11. When the movable 15 member is at its forward limit (determined by contact of said projections with the other member between the fingers thereof) the ends of said projections are forward of member 11, providing an entrance passage x. Hereinafter I designate by the term "fingers" those portions of 20 said projections 12b which in Fig. 4 are shown forward of the fingers 11c.

Member 12 is normally urged in the direction (backward) to enter its fingers between those 25 of member 11, thus: A sheet metal plunger 14 having a straight upper portion is bent forwardly and then down, as at 14a, and has its free end portion 14b bent rearwardly. A coupling between said member and the plunger is formed thus: 30 An elastic metal strip 15 forming the coupling is rebent, both legs thereof having opposed bends 15a whose concave sides or notches are relatively outward, one leg projecting further than the other to form a tongue 15b. With its legs straddling the rear leg of element 7 this coupling is 35 sprung into a hole 12x of the movable tension member 12 (the opposite edges of the member 12 at such hole engaging in the mentioned notches so that the coupling is fast to said member) and 40 the tongue 15b is entered freely into a hole or slot 14c of the plunger. When the plunger is elevated the member 12 is swung forwardly and when it is allowed to fall it swings said member rearwardly. Forming a depending extension of 45 the plunger is the stem 16a of a piston 16.

The plunger's movements are fluid-damped as follows: There is a cup 17 having a top external flange 17a and received in a hole 2a in web 2 and also having a circumferential slot 17b below the 50 web whereby, as will appear, the cup becomes a part of the fixed structure. This cup or cylinder receives the piston 16 here with a somewhat loose fit since a liquid, as water, partially filling the cup is in this example to be the damping medium for the inter-coupled plunger and member 12. To retain the liquid and exclude foreign matter that might interfere with the motion of the piston there is a cover 18 of quite flexible material and truncated-conical in form whose 55 lower margin is fitted over the flange 17a of the cup and whose neck-portion 18a embraces the stem of the piston, both joints (at the flange and stem) being of course hermetic. When the piston descends this cover undergoes pleating, bel- 60 lows-fashion.

To thread the device, the thread a being already reeved through the eye 4, the operator with, say, the right hand, draws it forward past the left side of the device and then, having lifted the 65 plunger with the other hand and hence shifted the movable tension member forwardly, passes the thread to the right and across the upper ends of the fingers of projections 12b whereupon it assumes a position between the two members or grids thus: Since the outer faces at said

ends of the fingers now converge toward the portions or fingers 11c the tautened thread is cammed by the fingers toward and past their free ends so as to enter passage x. Then, engaging the concave inner faces of the fingers 11c, which extend further than the fingers of the movable grid, it is cammed by them downwardly, so that when the intercoupled plunger and movable grid are now freed the thread remains held by and between the concave faces of the 10 fingers of both grids.

For the signaling the construction is as follows: A lever 19 has its body portion and an arm 19a thereof fulcrumed on the rear leg of element 7, to wit, at what I term the "draft" side 15 of the members 11-12 or the side thereof from which the thread is discharged, the body portion being outward of the right leg of the frame proper 2 and the arm bent off to overlie said leg and then bent forward to obtain its fulcrum on 20 said leg of member 7. This device has an upstanding thread-engaged arm 19b and gravity tends to urge said lever anti-clockwise as viewed from the right, or so that this arm moves through the line in which the thread is confined by the 25 grids to travel between them. When the device is threaded, as described, the lever is tilted by the attendant reversely and the thread passed in front of it, thus when taut to maintain the lower bent-off end 19c of the lever out of circuit-closing 30 position. An insulating plate 20 is secured to the bottom of the web 2 of the frame proper by screws 21, and incidentally this plate is notched at 20x and receives in its notch the cup 17, the edge of the plate at the notch being engaged 35 in the slot 17b of the cup, whereby the latter, with its flange 17a resting on the web, is held from upward displacement. Under the insulating plate is a metal terminal plate 22 having a forked terminal to which a wire X of the signaling 40 circuit is to be connected. This plate 22 is held fast by one of the screws 21 and also by having a forward band-portion 22a whose ends are bent upward, being received by notches 20a in plate 20, and then back over the latter. One 45 of such ends forms a contact to coact with the end 19c of the lever 19 to close the circuit when the lever is freed for that purpose. Screw 21 extends through a hole 22b in plate 22 of ample 50 diameter to avoid contact of the plate with the screw.

Occasionally some thread adjacent to but not under control by the particular tension device may become looped around the latter and thus or otherwise cause the circuit-closing lever 19 to close the circuit. To prevent this, 23 is a forwardly projecting curved guard, here a wire attached to the fixed structure as follows: The upper end of the wire has a hook which engages the forward leg of member 7 and is received in a slot 11d of the grid 11 and has its lower end engaged in a socket 20b of the insulating plate 20—not of course contacting with the terminal plate 22.

Having thus fully described my invention, what I claim is:

1. Thread tension means including fixed structure having a row of spaced thread-engaging portions and a member coactive with said structure to receive the thread to be tensioned and having, substantially parallel with the first row, a row of spaced fingers formed and arranged to enter the spaces between said portions, said member being normally urged to enter its fingers into but movable reversely to retract them 75

from said spaces and said structure limiting the reverse movement of said member to a position in which the fingers are retracted from said spaces and stand with their free ends in spaced relation to and projecting toward the first row, said fingers providing adjacent their free ends surfaces, remote from the first row when said member is in said position, which with said member in said position converge toward said portions.

2. In combination, fixed structure, a member having a row of spaced thread-engaging portions, said structure providing an axial support for said member extending substantially parallel with said row, an element affixed to said structure and overhanging said member in substantially parallel relation to said axial support, said member and element having an interlock confining the former against displacement around said support as an axis, and a back-and-forth-movable member opposite the first member and pivoted in said structure on an axis substantially parallel with said support and having a row of spaced thread-engaging portions and normally urged in one direction around its pivoting axis.

3. In combination, fixed structure having a portion in contact with which the thread to be tensioned travels in a generally horizontal line, a member opposed to said portion and in contact with which the thread, between them, travels, said member being pivoted on an axis substantially parallel with said line, and a plunger normally urging said member in the direction around said axis to press said member against the thread, said member and plunger having means to intercouple them for movement together in unison consisting of a tongue on one and a hole in the other receiving the tongue.

4. Means to damp the movements of the movable member of a yarn tension means including fixed structure, a piston, a fluid-containing cylinder arranged in said structure and having an open mouth receiving the piston, and a flexible cover of sheet material on the cylinder covering its mouth and penetrated by the piston and forming a hermetic seal therewith and with the cylinder.

5. In combination, with opposed tension members providing parallel rows of fingers arranged to intermesh and one of which members is movable and normally urged in the direction through the other and back, whereby when moved in the first direction to exert pressure on the thread to be tensioned and traveling between said members, supporting structure for said members, and a thread-engaged circuit-closing device pivoted in said structure on an axis parallel with said rows and movable from and toward circuit-closing position and normally urged toward said position and having a substantially straight thread-engaging surface extending transversely of its pivoting axis.

6. In combination, a frame, a fixed rebent elongated element having its legs substantially parallel and penetrating a portion of said frame, and a pair of opposed coactive tension members respectively supported by said legs, one member being pivoted and having the corresponding leg forming its pivoting axis and being normally urged in one rotative direction.

7. In combination, a frame, a fixed rebent elongated element having its legs substantially parallel and penetrating a portion of said frame, a pair of opposed coactive tension members respectively supported by said legs, one member being pivoted and having the corresponding leg forming its pivoting axis and being normally urged in one rotative direction and a thread-engaged circuit-closing device pivoted on one of said legs and normally urged in one rotative direction.

8. In combination, fixed structure, means therein to exert tension on the thread, means to damp the movements of the first means including a closed cylinder supported by said structure, the first means having a piston in the cylinder, a circuit-closing device normally urged against the thread, a contact arranged to be engaged by said device on failure of the thread, and an element fixed to, and insulating the contact from, said structure and confining the cylinder to said structure.

FREDERICK J. KENT.
